Primary Examiner — Caron D Veynar*Assistant Examiner* — Abraham Bahta(74) *Attorney, Agent, or Firm* — Fraser Clemens Martin & Miller LLC; James D. Miller(57) **CLAIM**

The ornamental design for a flexible container, as shown and described.

DESCRIPTION

FIG. 1 is perspective view of the first embodiment of the flexible container showing my new design;

FIG. 2 is a front elevational view thereof, the rear elevational view being identical;

FIG. 3 is a top plan view thereof;

FIG. 4 is a bottom plan view thereof;

FIG. 5 is a left side elevational view thereof; the right side elevational view being identical;

FIG. 6 is a perspective view of the second embodiment of the flexible container;

FIG. 7 is a front elevational view thereof, the rear elevational view being identical;

FIG. 8 is a top plan view thereof; wherein a bottom plan view not shown is identical to the bottom view elevational view of FIG. 4; and,

FIG. 9 is a left side elevational view thereof, the right side elevational view being identical.
